US00D572801S

(12) **United States Design Patent**
Kemp

(10) **Patent No.:** **US D572,801 S**
(45) **Date of Patent:** **** Jul. 8, 2008**

(54) **SPOUT**

(75) Inventor: **Douglas A. Kemp**, North Ridgeville, OH (US)

(73) Assignee: **Moen Incorporated**, North Olmsted, OH (US)

(**) Term: **14 Years**

(21) Appl. No.: **29/244,894**

(22) Filed: **Dec. 14, 2005**

(51) LOC (8) Cl. **23-01**

(52) U.S. Cl. **D23/255**

(58) Field of Classification Search D23/238-250, D23/253-255; 4/671-678; 137/801, 615

See application file for complete search history.

(74) Attorney, Agent, or Firm—Calfee, Halter & Griswold LLP

(57) **CLAIM**

The ornamental design for a spout, as shown and described.

DESCRIPTION

FIG. 1 is a perspective view of a spout of the new design;

FIG. 2 is a front elevation view thereof, shown at a larger scale;

FIG. 3 is a rear elevation view thereof, shown at a larger scale;

FIG. 4 is a left side elevation view thereof;

FIG. 5 is a right side elevation view thereof;

FIG. 6 is a top plan view thereof; and,

FIG. 7 is a bottom plan view thereof.

The portions of the Figures shown in broken lines are not part of the claimed design and are for illustration only.

1 Claim, 3 Drawing Sheets
